CLAIM

We claim, the ornamental design for a handheld controller for vehicles, as shown and described.

DESCRIPTION

FIG. 1 is a front perspective view of a handheld controller for vehicles, showing our new design;
FIG. 2 is a bottom plan view thereof;
FIG. 3 is a back elevational view thereof;
FIG. 4 is a left side elevational view thereof;
FIG. 5 is a right side elevational view thereof;
FIG. 6 is a front elevational view thereof;
FIG. 7 is a top plan view thereof; and,
FIG. 8 is a rear perspective view thereof.
